UNITED STATES PATENT OFFICE.

FRANCIS EDWARD MATTHEWS, OF BLACKHEATH, AND HENRY JAMES WHEELER
BLISS, OF STOCKWELL, LONDON, ENGLAND.

MANUFACTURE OF DIHALOGEN PARAFFINS.

1,158,524.

Specification of Letters Patent.

Patented Nov. 2, 1915.

No Drawing.

Application filed June 6, 1914. Serial No. 843,510.

To all whom it may concern:

Be it known that we, FRANCIS EDWARD MATTHEWS, Ph. D., F. I. C., a subject of the King of the United Kingdom of Great Britain and Ireland, and residing at Ash Lawn, The Glebe, Blackheath, in the county of Kent, England, and HENRY JAMES WHEELER BLISS, M. A., a subject of the United Kingdom of Great Britain and Ireland, and residing at Ingram House, Stockwell, in the county of London, England, have invented new and useful Improvements in the manufacture of Dihalogen Paraffins, of which the following is a specification.

15 The preparation of the dihalogen substitution derivatives of the paraffins having the halogen attached to different carbon atoms, is of considerable importance for the production of doubly unsaturated hydrocarbons and other products.

20 In obtaining dihalogen paraffins from the paraffins it has been proposed to prepare a monohalid, convert this to an olefin and add halogen to the latter or again the monohalid may be directly halogenated, yielding a dihalid. In either case, four atoms of halogen are required to convert one molecule of paraffin to one molecule of dihalid.

According to the present invention, the production of each molecule of dihalid requires only two atoms of halogen.

We obtain a mixture of saturated and unsaturated hydrocarbons including olefins in any suitable manner, for example, by heating a saturated paraffin hydrocarbon with or without the aid of a catalyst. It is difficult and in some cases impossible to separate the saturated and unsaturated hydrocarbons by fractionation. Similarly the product 35 which may be obtained by the halogenation of such a mixture contains a mixture of dihalids which are difficult to separate on account of the presence of other products, e. g. paraffins and a proportion of higher 40 and lower halids of varying molecular weights, some of which may have boiling points approximating to those of the desired dihalids. On the above account the cracked mixture thus obtained has hitherto 45 not been considered suitable for many chemical purposes. According to this invention we fractionate such a mixture so that the olefins in each fraction are chiefly olefins

with the same number of carbon atoms in the molecule, e. g. the isomeric C_5H_{10} olefins. 55 We treat the fraction so obtained either in the liquid condition, or in the condition of vapor, with halogen in sufficient quantity only to effect the saturation of the unsaturated hydrocarbons present, the halogenation being preferably carried out in the dark and at a low temperature and with the hydrocarbon in a state of dilution in order to avoid substitution.

In place of the halogen itself, or of part 65 thereof, we may use a substance capable of yielding halogen, the halogen and the halogen-yielding substance being hereinafter collectively referred to as "halogenizing 70 agents."

The progress of the reaction may be tested by adding a small quantity of bromin to a sample. The color of the bromin should persist for some time if sufficient halogen has already been added. The mixture obtained 75 by halogenation as aforesaid can easily be fractionated so as to separate the saturated hydrocarbons from the halids.

The following is an example of how this invention can be performed but it is not 80 limited thereto: A mixture of paraffins, containing paraffins $C_{10}H_{22}$ to $C_{12}H_{26}$ is cracked by heating; for example by passing the vaporized mixture through a hot tube or by placing in the vapor or in the liquid mixture 85 a wire which is electrically heated. The process may be carried on with or without the assistance of a catalyst, for example a metal such as nickel, and in the presence or not of steam or other diluent. The product 90 is then condensed. It contains a proportion of saturated and unsaturated hydrocarbons C_5H_{12} to C_6H_{14} and C_6H_{10} to C_6H_{12} . The condensed product is fractionated and the fractions containing unsaturated C_5 hydro- 95 carbons (b. p. 30° to 40°) and unsaturated C_6 hydrocarbons (b. p. 65° to 73°) are collected separately. Lower and higher fractions, if formed, may also be collected, or may be rejected and used as solvents or for 100 any other purpose to which they are applicable. The selected fractions are then treated with halogen as aforesaid, and fractionated to recover the dihalids, which may be used for any required purpose or be treated 105 in any suitable manner, for example, ac-

ording to the specification of the application for British Letters Patent No. 17234 A. D. 1912 to remove two molecular proportions of halogen acid, yielding doubly unsaturated hydrocarbons.

It is clear that in the above example the fractionation before halogenation may be in some cases carried out to narrower limits of temperature so that one isomeric olefin ¹⁰ alone is present; more generally however it is preferable to carry out any further separation by fractionating the halids.

We may also use other mixtures containing a proportion of unsaturated hydrocarbons and we do not limit ourselves to the hereinbefore described method of preparing an unsaturated mixture.

Certain mixtures may contain a proportion of doubly unsaturated hydrocarbons; ²⁰ for instance it is known that a proportion of butadiene is found in the gases produced by cracking. Such doubly unsaturated hydrocarbons may in some cases be recovered or separated for example by fractionation or ²⁵ polymerization or the halids may be recovered after halogenation has taken place. Similarly the halids of acetylenic hydrocarbons may be separated.

The residual gases, saturated hydrocarbons and fractions obtained in carrying out this invention may be used for fuel or for any other purpose to which they are applicable or they may in some cases be treated again in accordance with this invention.

Having now particularly described and ascertained the nature of our said invention

and in what manner the same is to be performed we declare that what we claim is:—

1. Process of preparing dihalogen substitution derivatives of the paraffin hydrocarbons which consists in subjecting a mixture containing olefin hydrocarbons and saturated hydrocarbons to fractional distillation so that the olefin hydrocarbons in each fraction are chiefly olefin hydrocarbons having the same number of carbon atoms in the molecule, and then treating the fractions with only sufficient halogenizing agents to effect the saturation of the unsaturated hydrocarbons and subsequently separating the dihalids by fractional distillation, substantially as described.

2. The process of preparing dihalogen substitution derivatives of the paraffin hydrocarbons, which consists in subjecting a mixture containing olefin hydrocarbons and saturated hydrocarbons to fractional distillation to obtain a fraction containing chiefly olefin hydrocarbons having the same number of carbon atoms in the molecule, and then treating said fraction with only sufficient halogenizing agent to effect the saturation of the unsaturated hydrocarbons, substantially as described.

In testimony whereof we have signed our names to this specification in the presence of two subscribing witnesses.

FRANCIS EDWARD MATTHEWS.
HENRY JAMES WHEELER BLISS.
